UNITED STATES PATENT OFFICE.

ERNEST W. LINDQUIST, OF LAWRENCE, MASSACHUSETTS.

SHAKE ARRANGEMENT FOR CYLINDER PAPER-MACHINES.

1,323,702.

Specification of Letters Patent.

Patented Dec. 2, 1919.

Application filed April 1, 1918. Serial No. 225,972.

To all whom it may concern:

Be it known that I, ERNEST W. LINDQUIST, a citizen of the United States, and resident of Lawrence, county of Essex, Commonwealth of Massachusetts, have invented an Improvement in Shake Arrangements for Cylinder Paper-Machines, of which the following description, in connection with the accompanying drawings, is a specification, like characters on the drawings representing like parts in each of the several views.

This invention relates to paper machines of the cylinder type. In machines of this type as heretofore used, the wire cloth or foraminous hollow cylinder operative in the pulp vat has by its rotary movement through the pulp tended to cause the pulp fibers to arrange themselves in a direction parallel with the plane of rotation so that by far the greater part of the fibers in the paper sheet extend lengthwise thereof and comparatively few crosswise. This has resulted in making the paper strong and tough in one direction, *i. e.*, to resist tearing across the web, but comparatively weak to resist tearing in a direction lengthwise of the web. A prime object of the present invention is to provide means coöperative with the cylinder mold in the pulp vat for acting on the pulp in a manner so as to arrange a substantial portion of the pulp fibers in a direction more or less lengthwise of the cylinder, *i. e.*, transverse of the web, thereby obtaining a crisscross arrangement of the fibers in the paper sheet and making the same of uniform strength and toughness in all directions. To this end I provide moving elements operative in the vat relatively close to the cylinder periphery and provide means for reciprocating said elements constantly at a predetermined rate with respect to the cylinder rotation in the operation of the machine. A further object is to provide novel means for mounting and operating such moving elements whereby the mounting therefor presents smooth continuous surfaces and is of a construction simple but effective for the purpose in view. The foregoing and other objects and advantages of the invention will more fully appear from the following detailed description, and the distinctive features of novelty will be pointed out in the appended claims.

Referring to the drawings:

Figure 1 is a lengthwise vertical section of a mechanism constructed in accordance with my invention on line 1—1 of Fig. 3;

Fig. 2 is a fragmentary sectional view 60 showing a detail of the mounting of the fiber arranging elements;

Fig. 3 is a transverse section on line 3—3 of Fig. 1;

Fig. 4 is a plan view on a reduced scale 65 showing a modification;

Fig. 5 is a transverse section on line 5—5 of Fig. 4; and

Fig. 6 is a transverse section corresponding to Fig. 5 but showing a further modified form.

A pulp vat is indicated at 10 having a usual hollow wire cloth or foraminous cylinder 11 operative therein and mounted on a usual tubular shaft 12 deriving motion 75 from the couch roll as usual and journaled in suitable bearings 14 (not fully shown, since neither these nor the frame work of the machine are essential to an understanding of the invention). In accordance with 80 my invention I provide a reciprocating device shown as composed of three rods 15, 16, 17 spaced apart around the periphery of the cylinder and mounted to slide lengthwise of the cylinder in bearings 18 85 at the ends of the vat. The rods 15, 16, 17 are secured together for simultaneous operation at the back end of the machine by a bar frame work 19 to which is pivotally connected at 20 an operating device 90 shown as a pitman 21 pivoted at 22 to a crank pin carried by an operating shaft 23, and adjustable radially with respect thereto to vary the throw of said crank pin and hence the range of reciprocation 95 of said device. The rods 15, 16, 17 have secured thereto a grid structure composed of a series of spaced apart strips or bands 24 which extend around the cylinder within the vat and in relatively close proximity to 100 the cylinder as best seen in Fig. 3. The strips or bands 24 which are preferably relatively thin, *i. e.*, about one-sixteenth of an inch in the direction transverse of the cylinder, and considerably thicker, *i. e.*, about 105 one-half inch in the direction of reciprocation, are secured to the rods 15, 16, 17 preferably by being slipped thereon with intermediate spacing thimbles formed as short pipe sections 25, with other longer 110

similar pipe sections 26, 27 at the end portions of the rods and the whole secured rigidly in assembled relation by nuts 28 threaded on the ends of said rods, the frame 19 being also preferably clamped in place by the same nuts. In this way as the grid structure formed by the strips or blades 24 is reciprocated in proximity to the wire cloth cylinder 11 and during the rotation 10 thereof in the operation of the machine, the pulp fibers which would otherwise tend to arrange themselves on said cylinder almost wholly circumferentially thereof, are largely turned into a more or less crosswise direction by engagement with said strip or blade members so that as the paper web is taken off of the cylinder the fibers are disposed in a crisscross arrangement which by properly proportioning the rate of reciprocation 15 of said grid with respect to the rotation of the cylinder may be made fairly uniform with respect to the lengthwise and crosswise components thereof. In Figs. 4 and 5 I show a form of the invention where- 20 in instead of having the three rods 15, 16, 17, I mount only two rods 15^a, 16^a in bearings 18^a at the top of the vat and secure in spaced apart relation on these respective rods, curved strips or blades 24^a, 24^b which 25 may extend down with their outer ends relatively close together at the bottom of the cylinder as seen at 24^c, these strips like the strips 24 curving around the cylinder in relatively close proximity thereto. In this 30 form of the invention the rods 15^a, 16^a are individually reciprocated by pitmen 21^a, 21^b engaged with crank pins 22^a, 22^b secured to an operating shaft 23^a at opposite sides thereof so that as said shaft is driven by 35 suitable means shown as a cone pulley 29, the two grids formed by the two series of strips 24^a, 24^b will be reciprocated in opposite directions. The strips or blades 24^a, 24^b in this form may be secured to the rods 40 15^a, 16^a in like manner as already described and they are also preferably relatively thin transversely and wider in the direction of reciprocation as already described, though as to both forms of the invention it is to 45 be understood that the particular proportions shown for these strips is merely illustrative and not restrictive and is intended to typify any suitable elements for operating in proximity to the web forming mold 50 whether such elements be in the form of bands or wire, or otherwise. In Fig. 6 I show a form wherein the reciprocating strips 24^c are mounted for a swinging movement lengthwise of the cylinder mold instead of a straight rectilinear movement 55 as in the first described forms. These strips

24^c are here pivoted to the top of the vat at 18^c and have upward extensions 24^e thereof above such pivots pivotally connected with reciprocating bars 15^b, 16^b which may be operated similarly as the rods 15^a, 16^a to keep the strips 24^c in constant swinging movement during the operation of the mechanism. The vat 10 is shown as divided by an intermediate partition 30 to form a 60 drainage chamber 31 at the front end of the machine with a passage leading thereto from the interior of the cylinder as is usual and the couch roll 32 with the felt 33 co-operative with the cylinder mold 11 may 65 be of any usual or suitable character. I am aware that the invention may be embodied in other specific forms without departing from the spirit or essential attributes thereof, and I therefore desire the 70 present embodiment to be considered in all respects as illustrative and not restrictive, reference being had to the appended claims rather than to the foregoing description to indicate the scope of the invention. 75

Having described my invention, what I claim as new and desire to secure by Letters Patent is:

1. Apparatus of the kind described comprising a pulp vat, a cylinder mold mounted to operate therein, and a grid mounted for reciprocation transverse of the plane of cylinder movement, said grid consisting in a plurality of rods with spaced apart strips extending from said rods and curving around a substantial portion of the cylinder mold, said strips being relatively thin in the direction transverse of the cylinder, and substantially thicker in the direction of reciprocation whereby requisite rigidity 95 thereof is attained along with the capability of passing through the pulp liquid without unduly agitating same. 100

2. Apparatus of the kind described comprising a pulp vat, a cylinder mold mounted to operate therein, and means mounted in proximity to said mold and movable in a direction transversely of the mold movement for arranging the pulp fibers transverse of the paper web, said means including a series of spaced apart strips, curving around a substantial portion of the cylinder mold, said strips being relatively thin in the direction transverse of the cylinder, and substantially thicker in the direction 115 of reciprocation whereby requisite rigidity thereof is attained along with the capability of passing through the pulp liquid without unduly agitating same. 120

In testimony wherof, I have signed my name to this specification.

ERNEST W. LINDQUIST.
